TYPEWRITING MACHINE

Max Garbell, Chicago, Ill., assignor to Victor
Adding Machine Company, Chicago, Ill., a cor-
poration of Illinois

Application August 24, 1931, Serial No. 558,864

41 Claims. (Cl. 197—27)

This invention relates to improvements in typewriting machines and has particular reference to an improved typewriter action mechanism; that is to say, the mechanism whereby the depression of the key buttons is transmitted to the corresponding type bars to effect printing operation thereof.

The primary object of the invention is to provide a typewriter action mechanism which shall be substantially noiseless, easy, and rapid in operation, the construction being relatively simple and inexpensive to build and advantageous in other respects.

Other objects and advantages of the invention will appear from a consideration of the detailed description of a preferred embodiment of the invention, appearing hereinafter, taken in conjunction with the accompanying drawings forming a part hereof, in which:

Figure 1 is a view, partly in side elevation and partly in vertical section, of a typewriter assembly embodying the present invention, showing only those parts of the construction which are essential to a complete understanding of the invention, the parts being shown in their positions of rest;

Fig. 2 is a view similar to Fig. 1 but showing one of the key levers and the corresponding type bar and associated parts of the action mechanism in printing position;

Fig. 3 is an exploded perspective view showing the individual parts of the action mechanism in substantially the same positions as in Fig. 2;

Fig. 4 is a fragmentary view showing one-half of a segment member on which certain parts of the mechanism are pivoted, this view being taken in the direction of the arrow 4 in Fig. 1;

Fig. 5 is a fragmentary view showing one half of another segment member in which the type bars are pivotally mounted, this view being taken in the direction indicated by the arrow 5 in Fig. 1;

Fig. 6 is a fragmentary side elevational view showing the essential parts of the action mechanism in their positions of rest;

Fig. 7 is a view similar to Fig. 6 but showing the same parts in the positions which they occupy at an intermediate point during the printing stroke;

Fig. 8 is a view similar to Figs. 6 and 7 but showing the type bar in printing position and the other parts of the mechanism in corresponding positions; and

Fig. 9 is a view substantially similar to Fig. 7 but enlarged to illustrate in greater detail cer-

tain features of the invention hereinafter described.

Referring to the drawings, Figs. 1 and 2 illustrate a suitable typewriter frame 11 in which a shiftable carriage support 12 is suitably supported by means of a pivot or rock shaft 13 which may be adjustably mounted as hereinafter mentioned. The carriage support preferably comprises a depending arm 12^a through which a suitable operative connection may be made to the usual shift keys for actuating the carriage support between its lower case and upper case positions. A platen carriage 14 is suitably mounted on the carriage support 12 by means of antifriction balls 15 disposed between cooperating raceways provided on the carriage support and platen carriage, to accommodate movement transversely of the machine, as is well known in the art. The platen carriage 14 carries a platen 16 which is rotatably mounted therein in the usual manner and which is shiftable between the position indicated in full lines and the position indicated by the dotted lines 16^a to accommodate lower case and upper case printing, respectively. It will be understood that the platen is actuated between these two positions by moving the carriage support 12 about its pivotal mounting 13 as a result of the usual shift key operation.

A plurality of key levers 17 are pivotally mounted on a pivot wire or rod 18 which is suitably secured in the machine frame near the rear portion thereof, and each of these key levers is provided with the usual key button 19 disposed in the desired keyboard arrangement. A portion 17^a of each of the key levers extends rearwardly from the pivotal support 18 and has attached thereto at its rear extremity one end of a tension spring 20, the other end of which is suitably connected to an angle member 21 secured to the bottom plate of the machine frame. The springs 20 thus serve to maintain the corresponding key levers in their positions of rest and to return them to such positions after each depression thereof.

For each of the key levers there is provided a corresponding type bar 22 which is pivotally mounted upon a pivot wire 23 carried in a transverse slot or groove in a type bar segment member 24 which is suitably secured in the machine frame, as by means of screws 25 securing the segment member to the side walls of the frame 11. The segment member 24 is provided with a plurality of longitudinal slots 24^a to receive the pivoted ends of the individual type bars 22 and to provide guides for a geared connection be-

tween each of the type bars and a corresponding intermediate member 26 for actuating the same.

The members 26 are pivoted upon a pivot wire 27 carried in a transverse slot or groove in a segment member 28 which is secured between the side walls of the machine frame in a manner similar to that in which the segment member 24 is mounted. The two segment members 24 and 28 are similarly inclined, as indicated in Figs. 1 and 2, and the segment member 28 is provided with a transverse slot 28^a for each of the intermediate members 26, these slots being in alignment with the corresponding slots 24^a in the segment member 24, so that all of the members 26 lie flat and are of the same length, with their pivoted ends lying in the slots 28^a in the segment member 28 and their opposite ends in the slot 24^a in the segment member 24.

Each of the intermediate actuating members 26 comprises a portion 26^a projecting downwardly and forwardly from a point near the pivoted forward extremity of said member. Each of these projecting portions 26^a is provided with a hole to receive a pin 29 carried at the upper extremity of the upwardly extending arm 30^a of a bell crank member 30. The segment member 28 is provided at its bottom portion with a plurality of slots 28^b to receive individually the elbow portions of the bell crank members 30, which are pivotally mounted upon a pivot wire 31 carried in a slot or groove in the member 28 extending transversely of the slots 28^b.

The second arm 30^b of each of the bell crank members 30 extends rearwardly from the pivot wire 31 and is pivotally connected at its rear extremity with the upper end of a link 32, the lower end of which is pivotally connected to the corresponding key lever 17 at an intermediate point thereon. It will be understood that the bell crank members 30 will be of varying shapes and sizes for the different key levers and intermediate members, so that the proper operative connection is made between each of the key levers and the corresponding intermediate member.

The several key levers 17 are preferably maintained in alignment and in their proper relative positions by means of a comb member 33 which is slotted as indicated at 33^a to receive the individual key levers. This comb member may be suitably mounted upon the front face of the segment member 28 by means of screws, one of which is indicated by the reference character 34.

Each type bar 22 carries a type head 35, which, in turn, carries a lower case type 36 and an upper case type 37. The types 36 and 37 are respectively adapted to move into printing relation to the platen 16, upon depression of the corresponding key button 19, when the platen is in its lower case and upper case positions 16 and 16^a, respectively. A type bar guide 38 is carried by a member 39 which may be suitably secured to the segment member 24 so that it extends upwardly therefrom to support the guide 38 adjacent the printing point on the platen. This guide operates in the usual manner to receive the extremity of each of the type bars 22 as the same is actuated to printing position and to guide the corresponding type head into the exact position required for printing at the proper point on the work carried by the platen.

For the purpose of securing the desired substantially noiseless operation of the action mechanism, each type bar 22 has pivotally connected thereto, near the outer extremity which carries the corresponding type head 35, one end of a

toggle link 40, the other end of which is pivotally connected to a second toggle link 41. The opposite extremity of this latter toggle link is formed with a curved portion 41^a extending around the pivot of the corresponding intermediate member 26 and then doubled over and pivotally connected by means of a pin 42 to a portion 26^b of said corresponding intermediate member 26 which extends forwardly from the pivot thereof.

Each of the forward extensions 26^b of the intermediate members 26 is bent at substantially right angles to the plane of the member to form a portion 26^c lying in a transverse plane adjacent the curved edge of the forward portion 41^a of the corresponding toggle link 41. This portion 26^c extends upwardly above the upper edge of the portion 26^b from which it is bent, and its upper extremity is bent forwardly at substantially right angles to provide a portion 26^d to which the upper extremity of a tension spring 43 is attached. The lower extremity of the spring 43 is connected to a forwardly extending projection 41^b of the forward extremity of the toggle link 41.

Figs. 4 and 5 show the segment members 28 and 24, respectively, in somewhat greater detail than Figs. 1 and 2 and illustrate the fact that the slots 28^a in the segment member 28 for receiving the pivoted ends of the intermediate members 26 and the slots 24^a in the segment member 24 for receiving the pivoted ends of the type bars 22 are progressively spaced further apart from the middle of the respective segments toward the ends thereof. This arrangement accommodates the greater spacing of the type bars toward the ends of the segments which is required by reason of the fact that the type heads on the bars nearer the ends of the segments must be set at a greater angle with respect to the type bars which carry them than those nearer the middle of the segment.

The operation of the mechanism herein disclosed as a preferred embodiment of the invention is accomplished by depressing the key buttons 19 in the conventional manner, these buttons and the portions of the corresponding key levers 17 in front of the pivot 18 being biased upwardly at all times by the tension springs 20. With this fact in mind, the operation will be best understood by reference to Figs. 6, 7, and 8, in which one of the key levers 17 is shown only in part, this part being a portion of the key lever located between the pivot 18 and the forward extremity of the key lever and including the part to which the link 32 of the action mechanism is pivotally connected.

When the parts of the mechanism are in their respective positions of rest, as illustrated in Fig. 6, the key lever 17 is in its uppermost position and the type bar 22 is in its foremost and lowermost position, with the toggle links 40 and 41 folded up between the bottom of the type bar and the top of the intermediate member 26. Upon depression of the proper key button, the key lever 17 is moved downwardly and pulls with it, by means of the link 32, the forwardly extending arm 30^b of the bell crank 30 which moves pivotally about the pivot 31. This movement results in the upwardly extending arm 30^a of the bell crank 30 being moved to the right, or rearwardly of the machine, the pin 29 which is carried by said arm 30^a being similarly moved and carrying with it the downwardly extending arm 26^a of the intermediate member 26. This intermediate member pivots about its support 27 so that its

5 rearmost or right-hand extremity moves upwardly and through its geared connection with the pivoted end of the type bar 22 causes the latter to rotate about its pivot 23 and to move from its position of rest toward its printing position.

In this movement, the toggle links 40 and 41 are unfolded and pulled along by the type bar 22, but, due to the manner of mounting these links with the outer extremity of the link 40 pivoted to the type bar 22 and the free extremity of the link 41 pivoted to the forward extension 26^b of the intermediate member 26, these links 40 and 41 do not change greatly in their positions relative to the type bar 22 and intermediate member 26, respectively, during a major portion of the movement of the type bar and intermediate member; that is to say, from the positions of rest illustrated in Fig. 6 to the intermediate position shown in Fig. 7, in which latter position the type bar has moved through possibly two-thirds of its total path of travel. Since there is a comparatively slight relative movement between the toggle link 41 and the intermediate member 26 up to this point, the tension spring 43 is extended 25 from its original position only a comparatively slight amount and therefore remains under a tension which is increased only slightly over its original tension.

As the type bar moves from an intermediate 30 position such as that illustrated in Fig. 7 to its printing position as shown in Fig. 8, the toggle links 40 and 41 are fully extended by a relatively rapid movement, and during this operation the spring 43 is fully extended and checks the tendency of the middle pivot of the toggle to move past the dead center position. Such action is definitely prevented by contact between the curved edge of the forward portion 41^a of the toggle link 41 and the rear surface of the transversely bent portion 26^c of the forward extremity of the intermediate member 26. This curved edge constitutes a heel portion which moves into contact with the portion 26^c by substantially a rolling action, which is, therefore, quite noiseless, especially since the impact is checked by the increased tension of the spring 43.

When the toggle links 40 and 41 are fully extended, as shown in Fig. 8, the type bar has moved to its printing position and is unable to move beyond this point because any further extension of the toggle links is impossible. In this position the toggle links, type bar, and intermediate member form substantially a triangle which is extremely rigid and very definitely determines 55 the extent of travel of the type bar, so that there is no actual impact between the type and the platen through the work sheet carried by the latter. The prevention of such impact eliminates substantially all of the noise which ordinarily results from the operation of a machine not embodying a noiseless action. It will be understood, of course, that suitable means may be provided for adjusting the position of the platen relative to the fully extended or printing position of the 60 type heads, to accommodate different numbers of carbon copies, thickness of paper etc., as is well known in the art of noiseless typewriters.

Upon release of the key button after a printing stroke, the corresponding spring 20 returns 70 its key lever to its original position, and the return of the other parts of the action mechanism is facilitated by the spring 43, which immediately begins to assist in pulling the toggle links toward their folded positions, thus accelerating the return 75 action. This return action is substantially

silenced by the provision of a sound-deadening rest of any suitable character for the type heads, such as that indicated in part at 44 in Figs. 1 and 2. It will be understood that this rest is so shaped and mounted that all of the type heads 5 will rest thereon when they are in their normal positions of rest.

Fig. 9 shows the essential parts of the action mechanism in enlarged proportions to illustrate in greater detail the operative connection between the intermediate actuating member 26 and the type bar 22, which, as previously noted, preferably comprises a geared connection. It will be noted that the gear teeth 22^a at the upper extremity of the geared portion of the type bar 22 are located at a greater distance from the pivot 23 of the type bar than are the lower teeth indicated at 22^b, and that the radius of the pitch circle of the teeth on the type bar progressively decreases from the former extremity to the latter. 15 The pitch circle of the teeth formed on the intermediate member 26 progressively increases in a like degree between the extremities 26^c and 26^d.

This arrangement provides an increasing ratio 20 of the gear element on the intermediate member 26 to that on the type bar 22 as the printing stroke progresses, so that the desired acceleration 25 of the type bars is obtained. Thus the type heads are advanced with greater force toward the end of their strokes but are more gradually brought 30 to rest at the printing point by the relatively rapid extension of the toggle links during the latter part of the stroke and the simultaneous extension of the spring 43. Thus the actual printing 35 operation is accomplished with considerable force but with relatively little actual impact, so that substantially all of the noise usually incident to such operation is eliminated.

The spring 43 is under some tension even when 40 the parts of the mechanism are in their positions of rest and thus serves to take up all lost motion between the type bar 22, intermediate member 26, and toggle links 40 and 41. This action further contributes to the elimination of noise, particularly between the gear elements of the type bar 22 45 and intermediate member 26. These gear elements are shown in exaggerated proportions in Fig. 9 to illustrate the slight clearance which must always exist between the cooperating gear teeth to permit free operation and which will also increase slightly due to wear as the machine is used.

Due to the action of the spring 43, this clearance will always be between the tops of the teeth on the type bar 22 and the bottoms of the teeth on the intermediate member 26, as indicated by 50 the letter C, throughout both the printing and the return strokes of the mechanism. All noise due to "back-lash" between the gear elements during the printing and return strokes of the mechanism is thus eliminated. The same is true 55 with respect to any looseness in the pivotal connections of the toggle links, since the spring 43 maintains these links and the type bar 22 and intermediate member 26 under continuous tension relative to one another throughout the printing and return strokes.

From the foregoing it will be seen that the present invention provides an improved typewriter action mechanism which is of comparatively simple design and inexpensive construction but which 70 is highly advantageous in producing a substantially noiseless and easily and rapidly operable machine.

While only one specific embodiment of the invention has been shown and described herein, it 75

will be readily understood by those skilled in the art that various changes and modifications in the details of construction and arrangement of parts may be made without departing from the spirit and scope of the invention.

What is claimed as new and is desired to secure by Letters Patent, therefore, is:

1. A typewriter action mechanism comprising a type bar, an actuating member having a fixed 10 pivot, a direct operative connection between said actuating member and type bar, and a pair of toggle links for limiting the movement of said type bar, one of said links being pivotally connected to said type bar and the other of said 15 links being pivotally connected at one of its ends

to said one of said links and at its other end to said actuating member at a point removed from the fixed pivot of the latter and from the direct connection between the latter and the type bar, 20 said actuating member serving independently of said toggle links to actuate said type bar.

2. A typewriter action mechanism comprising a pivoted type bar, an actuating member having a fixed pivot, a direct operative connection between 25 said actuating member and type bar, and a pair of toggle links for limiting the movement of said type bar, one of said links being pivotally connected to said type bar and the other of said 30 links being pivotally connected at one of its ends to said one of said links and at its other end to said actuating member at a point removed from the fixed pivot of the latter and from the direct connection between the latter and the type bar, said actuating member serving independently of said 35 toggle links to actuate said type bar.

3. A typewriter action mechanism comprising a type bar, an actuating member having a fixed pivot, an operative connection between said actuating member and type bar, and a pair of toggle 40 links for limiting the movement of said type bar, one of said links being pivotally connected to said type bar and the other of said links being pivotally connected at one of its ends to said 45 one of said links and at its other end to said actuating member at a point on the opposite side of the pivot of the latter from the connection between said actuating member and the type bar, said actuating member serving independently of said 50 toggle links to actuate said type bar.

4. A typewriter action mechanism comprising a pivoted type bar, an actuating member having a fixed pivot, an operative connection between said actuating member and type bar, and a pair of toggle links for limiting the movement of said 55 type bar, one of said links being pivotally connected to said type bar and the other of said links being pivotally connected at one of its ends to said one of said links and at its other end to said actuating member at a point on the opposite side of the pivot of the latter from the connection between said actuating member and the type bar, said actuating member serving independently of said 60 toggle links to actuate said type bar.

5. A typewriter action mechanism comprising a type bar, a member for actuating said type bar, a toothed operative connection between said actuating member and said type bar, and a pair of toggle links for limiting the movement of said type bar, one of said links being pivotally connected to said type bar and the other of said 65 links being pivotally connected to said actuating member.

6. A typewriter action mechanism comprising a pivoted type bar, a member for actuating said 70 type bar, a toothed operative connection between

said actuating member and said type bar, and a pair of toggle links for limiting the movement of said type bar, one of said links being pivotally connected to said type bar and the other of said links being pivotally connected to said actuating member. 5

7. A typewriter action mechanism comprising a type bar, a pivoted member for actuating said type bar, a toothed operative connection between said actuating member and said type bar, and a pair of toggle links for limiting the movement of said type bar, one of said links being pivotally connected to said type bar and the other of said links being pivotally connected to said actuating member. 10

8. A typewriter action mechanism comprising a pivoted type bar, a pivoted member for actuating said type bar, a toothed operative connection between said actuating member and said type bar, and a pair of toggle links for limiting the movement of said type bar, one of said links being pivotally connected to said type bar and the other of said links being pivotally connected to said actuating member. 15

9. A typewriter action mechanism comprising a type bar, a member for actuating said type bar, said actuating member and said type bar being formed and disposed with intermeshing gear teeth to provide an operative connection therebetween, and a pair of toggle links for limiting the movement of said type bar, one of said links being pivotally connected to said type bar and the other of said links being pivotally connected to said actuating member. 20

10. A typewriter action mechanism comprising a pivoted type bar, a member for actuating said type bar, said actuating member and said type bar being formed and disposed with intermeshing gear teeth to provide an operative connection therebetween, and a pair of toggle links for limiting the movement of said type bar, one of said links being pivotally connected to said type bar and the other of said links being pivotally connected to said actuating member. 25

11. A typewriter action mechanism comprising a type bar, a pivoted member for actuating said type bar, said actuating member and said type bar being formed and disposed with intermeshing gear teeth to provide an operative connection therebetween, and a pair of toggle links for limiting the movement of said type bar, one of said links being pivotally connected to said type bar and the other of said links being pivotally connected to said actuating member. 30

12. A typewriter action mechanism comprising a pivoted type bar, a pivoted member for actuating said type bar, said actuating member and said type bar being formed and disposed with intermeshing gear teeth to provide an operative connection therebetween, and a pair of toggle links for limiting the movement of said type bar, one of said links being pivotally connected to said type bar and the other of said links being pivotally connected to said actuating member. 40

13. A typewriter action mechanism comprising a pivoted type bar, an actuating member connected therewith and pivoted forwardly of the type bar pivot, and a pair of toggle links for limiting the movement of said type bar, said links being directly and pivotally connected to each other, one of said links being pivotally connected to said type bar and the other of said links being pivotally connected to said actuating member on the opposite side of the pivotal 45

mounting of the latter from the connection between said actuating member and said type bar.

14. A typewriter action mechanism comprising a pivoted type bar, an actuating member connected therewith and pivoted forwardly of the type bar pivot, a pair of toggle links for limiting the movement of said type bar, said links being directly and pivotally connected to each other, one of said links being pivotally connected to said type bar and the other of said links being pivotally connected to said actuating member on the opposite side of the pivotal mounting of the latter from the connection between said actuating member and said type bar, and resilient means coacting between said actuating member and said other of said links.

15. A typewriter action mechanism comprising a pivoted type bar, an actuating member therefor pivoted forwardly of the type bar pivot, a pair of toggle links for limiting the movement of said type bar, one of said links being pivotally connected to said type bar and the other of said links being pivotally connected to said actuating member forwardly of the pivotal mounting of the latter, said actuating member and said other of said links being extended forwardly from the pivotal connection therebetween, and resilient means coacting between said extensions.

16. A typewriter action mechanism comprising a pivoted type bar, an actuating member therefor pivoted forwardly of the type bar pivot, a pair of toggle links for limiting the movement of said type bar, one of said links being pivotally connected to said type bar and the other of said links being pivotally connected to said actuating member forwardly of the pivotal mounting of the latter, said actuating member and said other of said links being extended forwardly from the pivotal connection therebetween, and a tension spring coacting between said extensions to maintain said type bar, actuating member and toggle links under continuous tension relative to one another.

17. A typewriter action mechanism comprising a pivoted type bar, an actuating member having a fixed pivot and directly connected to said type bar, a pair of toggle links for limiting the movement of said type bar, said links being directly and pivotally connected to each other, one of said links being pivotally connected to said type bar and the other of said links being pivotally connected to said actuating member, and resilient means for maintaining said type bar, actuating member and links under continuous tension relative to one another.

18. A typewriter action mechanism comprising a pivoted type bar, a pivoted member for actuating said type bar, a toothed operative connection between said actuating member and said type bar, a pair of toggle links for limiting the movement of said type bar, one of said links being pivotally connected to said type bar and the other of said links being pivotally connected to said actuating member, and resilient means for maintaining said type bar, actuating member and links under continuous tension relative to one another.

19. A typewriter action mechanism comprising a pivoted type bar, a pivoted member for actuating said type bar, said actuating member and said type bar being formed and disposed with intermeshing gear teeth to provide an operative connection therebetween, a pair of toggle links for limiting the movement of said type bar, one of said links being pivotally connected to said type

bar and the other of said links being pivotally connected to said actuating member, and resilient means for maintaining said type bar, actuating member and links under continuous tension relative to one another.

20. A typewriter action mechanism comprising a pivoted type bar, an actuating member having a fixed pivot and directly connected to said type bar, a pair of toggle links for limiting the movement of said type bar, one of said links being pivotally connected to said type bar and the other of said links being pivotally connected to said actuating member, and spring means coacting between said actuating member and said other of said links to maintain said type bar, actuating member and links under continuous tension relative to one another.

21. A typewriter action mechanism comprising a pivoted type bar, a pivoted member for actuating said type bar, a toothed operative connection between said actuating member and said type bar, a pair of toggle links for limiting the movement of said type bar, one of said links being pivotally connected to said type bar and the other of said links being pivotally connected to said actuating member, and spring means coacting between said actuating member and said other of said links to maintain said type bar, actuating member and links under continuous tension relative to one another.

22. A typewriter action mechanism comprising a pivoted type bar, a pivoted member for actuating said type bar, said actuating member and said type bar being formed and disposed with intermeshing gear teeth to provide an operative connection therebetween, a pair of toggle links for limiting the movement of said type bar, one of said links being pivotally connected to said type bar and the other of said links being pivotally connected to said actuating member, and spring means coacting between said actuating member and said other of said links to maintain said type bar, actuating member and links under continuous tension relative to one another.

23. A typewriter action mechanism comprising a key lever, a type bar, an intermediate member extending substantially horizontally fore and aft of the machine, a fixed pivotal support for the forward end of said intermediate member, a direct, contactive operative connection between the rear end of said intermediate member and said type bar, a pivotally mounted bell crank located below said intermediate member and having its arms respectively extending upwardly and rearwardly from the pivotal axis thereof, a direct pivotal connection between said upwardly extending arm and said intermediate member, and an operative connection between said rearwardly extending arm and said key lever.

24. A typewriter action mechanism comprising a key lever, a type bar, an intermediate member in operative engagement with said type bar, a link having one end connected to said key lever, a bell crank having one of its arms connected to the other end of said link and its other arm connected to said intermediate member, and a pair of toggle links for limiting the movement of said type bar, one of said toggle links being pivotally connected to said type bar and other other to said intermediate member.

25. A typewriter action mechanism comprising a key lever, a type bar, an intermediate member having a toothed operative connection with said type bar, a fixed pivotal support for said intermediate member, a link having one end con-

nected to said key lever, and a bell crank having one of its arms connected to the other end of said link and its other arm directly and pivotally connected to said intermediate member.

5 26. A typewriter action mechanism comprising a key lever, a type bar, an intermediate member having a toothed operative connection with said type bar, a fixed pivotal support for said intermediate member, a link having one end connected to said key lever, a bell crank having one of its arms connected to the other end of said link and its other arm directly and pivotally connected to said intermediate member, and a pair of toggle links for limiting the movement of said type bar.

10 27. A typewriter action mechanism comprising a key lever, a type bar, an intermediate member having a toothed operative connection with said type bar, a link having one end connected to said key lever, a bell crank having one of its arms connected to the other end of said link and its other arm connected to said intermediate member, and a pair of toggle links for limiting the movement of said type bar, one of said toggle links being pivotally connected to said type bar and the other to said intermediate member.

15

20

25

28. A typewriter action mechanism comprising a key lever, a type bar, an intermediate member, a fixed pivotal support for said intermediate member, said type bar and said intermediate member being formed and disposed with intermeshing gear teeth to provide an operative connection therebetween, a link having one end connected to said key lever, and a bell crank having one of its arms connected to the other end of said link and its other arm directly and pivotally connected to said intermediate member.

29. A typewriter action mechanism comprising a key lever, a type bar, an intermediate member, a fixed pivotal support for said intermediate member, said type bar and said intermediate member being formed and disposed with intermeshing gear teeth to provide an operative connection therebetween, a link having one end connected to said key lever, a bell crank having one of its arms connected to the other end of said link and its other arm directly and pivotally connected to said intermediate member, and a pair of toggle links for limiting the movement of said type bar.

50 30. A typewriter action mechanism comprising a key lever, a type bar, an intermediate member, said type bar and said intermediate member being formed and disposed with intermeshing gear teeth to provide an operative connection there-
55 between, a link having one end connected to said key lever, a bell crank having one of its arms connected to the other end of said link and its other arm connected to said intermediate member, and a pair of toggle links for limiting the movement of
60 said type bar, one of said toggle links being pivotally connected to said type bar and the other to said intermediate member.

31. A typewriter action mechanism comprising a key lever, a type bar, an intermediate member in operative engagement with said type bar, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and resilient means for maintaining said type bar, intermediate member

and toggle links under continuous tension relative to one another.

32. A typewriter action mechanism comprising a key lever, a type bar, an intermediate member having a toothed operative connection with said type bar, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and resilient means for maintaining said type bar, intermediate member and toggle links under continuous tension relative to one another. 15

33. A typewriter action mechanism comprising a key lever, a type bar, an intermediate member, said type bar and said intermediate member being formed and disposed with intermeshing gear teeth to provide an operative connection therebetween, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and resilient means for maintaining said type bar, intermediate member and toggle links under continuous tension relative to one another. 20 25 30

34. A typewriter action mechanism comprising a key lever, a type bar, an intermediate member in operative engagement with said type bar, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and spring means coacting between said intermediate member and said other of said toggle links to take up all lost motion all lost motion between said parts. 45

35. A typewriter action mechanism comprising a key lever, a type bar, an intermediate member having a toothed operative connection with said type bar, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and spring means coacting between said intermediate member and said other of said toggle links to take up all lost motion between said parts. 50 55 60 65

36. A typewriter action mechanism comprising a key lever, a type bar, an intermediate member, said type bar and said intermediate member being formed and disposed with intermeshing gear teeth to provide an operative connection therebetween, a link having one end connected to said key lever, a bell crank having one of its arms connected to the other end of said link and its other arm connected to said intermediate member, a pair of toggle links for limiting the movement of said type bar, one of said toggle links being pivotally connected to said type bar and the other to said intermediate member, and spring means coacting between said intermediate member and said bell crank.

diate member and said other of said toggle links to take up all lost motion between said parts.

37. A typewriter action mechanism comprising a key lever, a type bar, an intermediate member having a fixed pivot and a direct connection with said type bar for actuating the latter, a pair of toggle links for limiting the movement of the type bar, one of said links being pivotally connected to said type bar and the other of said links being pivotally connected to said intermediate member so that said links are substantially fully extended when said type bar is in printing position, and means for preventing the middle pivot of said toggle links from moving beyond the line connecting the end pivots of said links.

38. A typewriter action mechanism comprising a key lever, a type bar, an intermediate member for actuating said type bar, a pair of toggle links for limiting the movement of the type bar, one of said links being pivotally connected to said type bar and the other of said links being pivotally connected to said intermediate member so that said links are substantially fully extended when said type bar is in printing position, and means for preventing the middle pivot of said toggle links from moving beyond the line connecting the end pivots of said links, said means comprising portions of said intermediate member and said other of said links arranged to come gradually into engagement as the parts of the mechanism move from their positions of rest into printing position.

39. A typewriter action mechanism comprising a key lever, a type bar, an intermediate member for actuating said type bar, a pair of toggle links for limiting the movement of the type bar, one of said links being pivotally connected to

said type bar and the other of said links being pivotally connected to said intermediate member so that said links are substantially fully extended when said type bar is in printing position, and means for preventing the middle pivot of said toggle links from moving beyond the line connecting the end pivots of said links, said means comprising a projecting portion of said intermediate member adjacent the end pivot of said other of said links and a portion of said link extending substantially transversely of its length and constituting a curved heel portion arranged to come into abutting engagement with said projecting portion of said intermediate member by substantially a rolling action as the parts of the mechanism are actuated into printing position.

40. A typewriter action mechanism comprising a key lever, a type bar, an actuating member coacting therebetween and having a fixed pivot and a direct connection with said type bar, a pair of toggle links connected between the actuating member and the type bar for limiting the movement of the latter, and resilient means coacting between said actuating member and one of said links.

41. A typewriter action mechanism comprising a key lever, a type bar, an actuating member coacting therebetween and having a fixed pivot and a direct connection with said type bar, a pair of toggle links connected between the actuating member and the type bar for limiting the movement of the latter, and a tension spring coacting between said actuating member and one of said links to maintain said type bar, actuating member and toggle links under continuous tension relative to one another.

MAX GARBELL.

CERTIFICATE OF CORRECTION.

Patent No. 2,005,185.

June 18, 1935.

MAX GARBELL.

It is hereby certified that error appears in the printed specification of the above numbered patent requiring correction as follows: Page 5, first column, lines 7, 8 and 9, claim 14, strike out the words and comma "said links being directly and pivotally connected to each other, "; same page, second column, line 69, claim 24, for "other" first occurrence read the; and page 6, second column, line 46, claim 34, strike out the words "all lost motion"; and that the said Letters Patent should be read with these corrections therein that the same may conform to the record of the case in the Patent Office.

Signed and sealed this 13th day of August, A. D. 1935.

Leslie Frazer
